TELEPHONE SYSTEM

William Hatton and Leslie B. Haigh, Paris, France, assignors to Western Electric Company, Incorporated, New York, N. Y., a corporation of New York

Application September 13, 1933, Serial No. 689,191
In France September 21, 1932

18 Claims. (Cl. 179—7.1)

This invention relates to telephone systems and more particularly to measured-service multi-office telephone systems.

The object of the invention is to minimize the apparatus required for timing telephone calls and secure more efficient and economical use of such apparatus.

According to the invention, the apparatus required for timing interoffice telephone calls is located in a tandem office, the trunking arrangement being such that all such connections are routed through one or more tandem offices. As applied to a rural network which includes a number of outlying or satellite offices, the timing apparatus is located in the main office.

A feature of the invention relates to satellite systems, arranged for time and zone metering, in which the zone metering apparatus for controlling the operation of a calling subscriber's meter is located in the originating office. According to this feature, a conversational circuit in a main office, forming a part of a connection on a call originating in the main office or any of its satellite offices, is arranged to transmit metering impulses once only or at the beginning of each unit period of conversation for a call originated by a subscriber of the main office, and to transmit a timing signal over the talking circuit of a connection to the originating office at the beginning of each measured unit period of conversation for a call originated by a subscriber of a satellite office.

A further feature of the invention, relating to satellite systems arranged for time metering in which timing apparatus located in the main exchange is adapted to transmit a signal at the beginning of each measured unit period of conversation, is that the signal consists of the usual release initiating signal, in response to which a connection may be broken down, followed by a cancelling signal before release has been effected. Thus, a momentary opening of the talking circuit followed by reclosure may constitute the timing signal, the release of the connection being effected by an opening maintained until release has occurred.

A further feature relates to satellite systems arranged for time and zone metering wherein calls to certain zones may be metered a certain number of times for each measured unit period of conversation and may be limited in duration to a definite number of such unit periods, whereas calls to other zones may be metered solely at the beginning of a conversation and be unlimited in duration. According to this feature, a conver-

sational circuit, in a main office and forming a part of a connection on a call originating in the main office or any of its satellite offices, is arranged to cause operation of the calling subscriber's meter once only irrespective of the duration of the call or to cause operation of the meter at every measured unit period of conversation with or without limit of the duration in accordance with the origin of the call and its destination.

The drawings which form a part of this specification disclose in schematic form a system arranged in accordance with the features of this invention. The invention is not limited in its application to the particular system shown in the drawings.

Referring to the drawings—

Fig. 1 shows a schematic layout of the system which includes a satellite office SE and a main office CE;

Fig. 2 shows a subscriber's station S1, a link LK comprising the line-finder SLB and a trunk-selector SS, and an outgoing junction circuit OJC, all of which are in a satellite office;

Fig. 3 shows an incoming junction circuit IJC, subscribers' stations S2 and S3, a primary line-finder LF1, a link LK1 comprising the secondary line-finder LF2 and first selector SS1, a second selector SS2 and a final selector CS.

The origination of a call by the subscriber at station S1 in the satellite office causes this subscriber's line to be extended by a link comprising switches SLB and SS to an idle outgoing junction circuit OJC and over the junction J to the incoming junction IJC in the main office. Seizure of the outgoing junction causes a meter control circuit MCC to be operatively associated with the outgoing junction circuit OJC and causes the secondary line-finder LF2 of an idle link LK1 in the main office to hunt for and connect with the incoming junction IJC. An idle register controller RC is thereupon operatively associated with the link comprising the secondary line-finder LF2 and first selector SS1. When the calling subscriber at station S1 dials the number of the subscriber's station with which a connection is desired, the office-code digits are registered in the meter control circuit MCC of the satellite office and also in the register controller RC of the main office. The register controller controls the operation of the first selector SS1 and succeeding intermediate and final selectors such as SS2 and CS to complete the connection between the calling station S1 in the branch office and a called station S2 in the main office, or some other office. Zone metering apparatus in the outgoing junction cir-

cuit OJC is selectively positioned under the control of the meter control circuit MCC in accordance with the office code; and zone metering apparatus in the link comprising the line-finder 5 LF2 is selectively positioned in accordance with the office code under the control of the register controller RC. The zone metering apparatus in the link circuit of the main office is arranged to send back a single signal over the junction J at 10 the beginning of each three-minute period during which a talking connection is maintained between the calling and called stations; in response to this signal, the zone metering apparatus of the outgoing junction OJC causes the operation of 15 the calling subscriber's service meter once, twice or three times according to the office in which the called station is located. If the calling subscriber does not release the connection by replacing the receiver on the receiver hook before 20 the end of the fourth three-minute period, the connection is automatically opened, a warning tone having been transmitted over the talking connection ten seconds before the end of the twelve minutes.

25 The origination of a call by the subscriber at station S3 in the main office causes the operation of a primary line-finder such as LF1 to hunt for and connect with the calling line; the secondary line-finder LF2 of an idle link such as LK1, is 30 operated to connect with the line-finder LF1, and an idle register controller RC is thereupon operatively associated with this link. The calling subscriber dials the called subscriber's number and the connection is completed under control 35 of the register controller RC. The zone metering apparatus in the link is selectively positioned in accordance with the office-code registered in the controller RC to operate the calling subscriber's service meter as required. If the call is a local 40 call the meter is operated once only and the duration of the call is not limited. On interoffice calls the meter is operated twice or three times at the beginning of each three minute period during 45 which the talking connection is maintained and the connection is automatically broken down at the end of twelve minutes.

The operation of the system shown schematically in Fig. 1 having been described in general, attention will now be given to this system as disclosed in Figures 2 and 3. Referring to Fig. 2, 50 the subscriber's station S1 is connected by a line 10 to terminals in the bank of the finder switch SLB in a branch office. The selector switch SS is permanently connected to the line finder SLB; 55 together the line-finder and the selector form the link circuit LK. The subscriber's station equipment is of the usual type employed in automatic telephone systems and includes a dial or impulse sending device for use in establishing connection 60 with any other station as desired. The line circuit apparatus individual to line 10 in the branch office is represented by the service meter 15. These line and link circuits may be similar to those shown in Fig. 1 of the patent to W. Hatton 65 et al. No. 1,831,387 granted November 10, 1931, and reference may be had to this patent for a description of the operation of these circuit units.

The outgoing junction circuit OJC, which is 70 one of a group of such circuits to which the selector SS has access, is substantially the same as that shown in Fig. 2 and described in the specification of the aforementioned Patent No. 1,831,387 except that there is no clock circuit and timing switch available in the branch office for controlling the advance of the metering switch. All

apparatus included in the circuit unit OJC other than that required for a clear and complete description of this invention has been omitted. This circuit as shown includes an incoming supervisory relay 21, an outgoing supervisory relay 22, and a 5 release relay 24. Associated with the outgoing junction circuit is a metering switch SMS comprising the stepping magnet 30 and three brushes 31, 32 and 33 with their associated banks of terminals, the zone relays 34 and 35, and the control 10 relays 36 and 37. The meter control circuit MCC which receives and records the office-code digits of the number dialed by the calling subscriber is similar to that shown in Fig. 3, and described in the specification, of the aforementioned Patent 15 No. 1,831,387.

The junction J, to which the outgoing junction circuit OJC is connected, terminates at the main office in the incoming junction circuit IJC shown in Fig. 3. The line conductors of the incoming junction circuit are connected to terminals in the bank of the line-finder LF2 which together with the first selector SS1 forms a main office link circuit LK1 similar to that shown in Fig. 15, and described in the specification, of the aforementioned 25 Patent No. 1,831,387. The main office subscriber's station S3 and associated line circuit which is represented by the service meter 55 are also the same as the station and line circuits shown in Fig. 15, and described in the specification, of said patent. The primary line-finder LF1 which is represented by a set of brushes and the one set of terminals may be similar to that disclosed in the patent to E. P. G. Wright No. 1,901,940 granted March 21, 1933. The register controller RC, which receives and records the office-code digits of the number dialed by the calling subscriber at the same time that they are received and registered in the branch office meter control circuit MCC, is the same as that shown 40 in Figs. 9 and 10, and described in the specification, of the aforementioned Patent No. 1,831,387. The intermediate group and final selectors, SS2 and CS, each represented schematically by a set of brushes and one set of terminals, are similar to the group selector shown in Fig. 14 and the final selector shown in Figs. 12 and 13, and both described in the specification, of the aforementioned 45 Patent No. 1,831,387.

A call having been originated by the subscriber 50 at station S1 in the branch office, the line 10 is extended by the line-finder SLB and the selector SS to an idle outgoing junction circuit OJC. Upon seizure of OJC, the operation of relay 21 causes the meter control circuit MCC to be operatively associated with the junction circuit and also causes the main office end of the junction J to be extended by the line-finder LF2 of an idle link circuit to the associated selector SS1, all as described in the aforementioned Patent 1,831,387. 60 The finding of junction line J by the finder LF2 causes the operation of relays 43 and 44 of the incoming junction circuit IJC and also causes the operative association of the register controller RC with the link LK1 as described in the aforementioned Patent 1,831,387. When the number of the called station is dialed, the response of relay 21 is effective to repeat the dial impulses to the meter control circuit MCC and also over the junction J to relay 71 of the main office link 70 circuit; and relay 71 repeats the impulses to the associated register-controller RC. The operation of the first selector SS1 is thereafter controlled by the register-controller RC to make the required group selection. Intermediate and final selectors 75

such as SS2 and CS are operated under control of the register-controller RC to complete the connection to the called line which is designated 100; selectors SS2 and CS and line 100 may be 5 in the same office, as that in which the link LK1 is located, or in another office. Relays 21, 22, and 24 of the outgoing junction circuit OJC, relays 43 and 44 of the incoming junction circuit IJC, and relays 65, 66, 67 and 71 of the link circuit 10 LK1 are all operated. Relays 34 and 35 of the outgoing junction circuit OJC are each operated or normal depending upon the zone within which the called station is located as indicated by the office-code registered in the meter control circuit 15 MCC. Relays 76 and 77 of the main office link circuit LK1 are also each operated or normal depending upon the zone within which the called station is located as indicated by the office-code registered in the register-controller RC. For a 20 complete description of the operation of the various circuit units involved in completing a connection, reference may be had to the aforementioned Patent No. 1,831,387.

If the call originates at station S3 in the main 25 office, the calling line is extended by the operation of the primary line-finder LF1 and the secondary line-finder LF2 to the link LK1, a register-controller RC is operatively associated with the link, and the connection is completed 30 through an intermediate group selector and a final selector to the called line in the same or another office.

When the receiver is removed at the called station, supervisory relay 74 operates and closes a 35 circuit for operating relay 75. Relay 75 locks under control of relay 67 and if either of the zone indicating relays 76 or 77 is operated, relay 78 is operated due to the energization of its left winding. Relay 78 closes a locking circuit 40 through its left winding under control of relay 75 and closes a circuit for operating the start relay 85 of the timing switch TS. If neither of relays 76 or 77 is operated but the call is one originating in the branch office, relay 78 is operated 45 as hereinafter described. The operation of relay 75 also closes a circuit for advancing the metering switch SM out of normal position; this circuit is traced from battery through the winding of stepping magnet 90, through the brush 50 and normal contact of bank 91, the middle right front contact of relay 75, through interrupter 94 to ground. After the switch SM is moved out of 55 normal position, the magnet 94 is operated each time the interrupter closes the connection to ground thereby advancing the switch step-by-step to the last off-normal position.

Assuming the call to have originated in the 60 branch office, the advance of switch SM to its first off-normal position closes a circuit from ground through the right winding of relay 78, first off-normal terminal and brush 92 of switch SM, to brush 64 of line-finder LF2 and through the terminal with which brush 64 is in contact, to cause the momentary operation of relay 45 of 65 the incoming junction circuit IJC and the operation of relay 78. Relay 78 locks and closes the circuit for operating the start relay 85 of timing switch TS. In off-normal positions 3, 7 and 8, and 9 to 11 inclusive, connections are closed from battery 95 through the contacts of zone relays 70 76 and 77 dependent upon whether these relays are operated or normal, to brush 64 of line-finder LF2; but these connections are ineffective to cause the operation of relay 45. The aforemen-

tioned operation of start relay 85 closes a circuit from the stepping magnet 80 of timing switch TS to the clock circuit 86 whereby the switch TS is advanced to immediately open the connection between the springs of cam 84 and hold it open 5 for a period of twelve minutes. At cam 84, a connection is temporarily closed through its springs 3 minutes, 6 minutes, and 9 minutes after the switch is advanced out of normal position, thereby causing the switch SM to return to normal 10 and then repeat its cycle of operations 3 minutes, 6 minutes, and 9 minutes after its first cycle. At the end of 11 minutes and 50 seconds after the switch TS begins to advance, the cam 83 closes a connection from ground through the right winding of tone source 79, inner right front contact of relay 75, through the springs of cam 83 to condenser 72, a tone being thereby transmitted to the calling subscriber to indicate that the connection is about to be broken down. Cam 20 82 closes a connection through its springs 12 minutes after the switch TS begins to advance, thereby short-circuiting and causing the release of relay 65. The release of relay 65 causes the 25 release of relays 67 and 75, thereby breaking down the connection by causing the return of the line-finder LF2 to normal.

The operation of relay 45 at the beginning of each cycle of the advance of switch SM causes 30 a temporary opening of the lower talking conductor of junction J, ground being connected through the front contact of relay 45 to prevent the release of relay 71 due to this temporary operation of relay 45. The temporary opening of 35 the lower conductor of junction J at the beginning of each three minute period of conversation, after the called subscriber answers, causes a corresponding temporary release of the supervisory relay 22 of the outgoing junction circuit OJC. 40 The release of relay 22 causes the release of relay 24 and closes a circuit for operating relay 36. Relay 36 locks through its inner left front contact through the normal terminal and brush of bank 32 to ground; all off-normal terminals 45 of this bank except the last are strapped to the normal terminal so as to hold relay 36 until switch SMS reaches the last of its off-normal positions. As soon as relay 22 reoperates (due to the release of relay 45), relay 24 reoperates 50 and a circuit is closed for operating relay 37. Since the release of relays 22 and 24 is temporary the connection is maintained even though this metering signal is similar to the release signal. Relay 37 locks under control of relay 36 and connects interrupter 38 to the winding of the stepping magnet 30 of switch SMS thereby causing the 55 advance of this switch step-by-step until it reaches its last off-normal position. During the time that relay 24 is released, a circuit is closed through the winding of thermostatic relay 25 which requires a thirty second energization to cause its operation and the consequent release of the link LK. The circuit for operating the 60 calling subscriber's service meter 15 is closed during the advance of switch SMS by the non-bridging brush of bank 33 either once, twice, or three times, dependent upon the operated or normal condition of the zone relays 34 and 35. Thus 65 with relays 34 and 35 both operated, the operating circuit for service meter 15 is closed in each of positions 10, 11 and 12 of the switch SMS; with relay 35 operated and relay 34 normal the operating circuit for meter 15 is closed in each 70 75

of positions 8 and 9; and with neither of relays 34 or 35 operated, which condition exists on a call between subscribers both located in the branch office, the meter operating circuit is closed only in position 5. When the switch SMS reaches the last off-normal position, relays 36 and 37 are released and magnet 30 reoperates to ground at its own back contact to advance the brushes 31, 32 and 33 to normal position. The 10 operation of switch SMS is repeated at the end of 3 minutes, 6 minutes and 9 minutes of conversation due to the temporary release of relay 22 as controlled by the above described operation of switches SM and TS in the main office.

15 When the calling subscriber releases the connection, relay 21 releases thus opening the supervisory loop over junction J whereby relay 22 of the outgoing junction circuit OJC and relay 71 of the main office link circuit LK1 are released. 20 The release of relay 71 causes the release of relay 67 and the return of the link LK1 to normal. The release of relay 22 causes the release of relay 24 and the continued energization of the winding of thermostatic relay 25. The operation of relay 25 at the end of 30 seconds causes the release of the link LK and return of switches SLB and SS to normal.

On calls originating from station S3 in the main office, the advance of switch SM closes the operating circuit for service meter 55 in each of positions 9, 10 and 11 if zone relays 76 and 77 are both operated, in each of positions 7 and 8 if relay 77 only is operated, and in position 3 if neither of relays 76 nor 77 is operated. If the 30 called station is in the same office with station S3, the switch SM does not repeat its cycle of operations since none of relays 76, 77 and 78 are operated and the start relay 85 of the timing switch TS is not operated; the conversation may 35 therefore continue, without interruption for 12 minutes, and metering occurs only at the beginning of the conversation.

In the system shown in Figs. 2 and 3, it is seen that the timing switch TS and controlling 45 clock mechanism 86 at the main exchange are employed in timing all calls, except local calls, originated in both the branch and main offices, there being no timing apparatus or clock mechanism in the branch office.

50 What is claimed is:

1. In a measured-service telephone system, subscribers' lines, a branch office, a main office, a conversational circuit unit in said main office for use in completing calls originating in said main office and for completing calls originating in said branch office, means for extending a connection from a calling line in said branch office to said conversational circuit unit, and timing means in said conversational circuit unit for transmitting 55 a timing signal over the talking connection to said branch office at the beginning of each measured unit period of time during which a talking connection is maintained on a call originating in said branch office.

60 2. In a measured-service telephone system, subscribers' lines, a branch office, a main office, means for extending a connection from a calling line in said branch office to said main office, apparatus in said main office for counting off unit 65 periods of time during which a talking connection is maintained on calls originating in, terminating at, or routed through said main office, and means controlled by said apparatus for transmitting a timing signal to said branch office at the begin-

ning of each of such unit periods on calls originating in said branch office and for charging the calling subscriber for each of such unit periods on calls originating in said main office.

3. In a measured-service telephone system, 5 subscribers' lines, a branch office, a main office, means for extending a connection from a calling line in said branch office to said main office, apparatus in said main office for counting off unit periods of time during which a talking connection 10 is maintained on calls originating in, terminating at, or routed through said main office, means in said main office for transmitting a release signal on calls originating at said branch office to cause release of the connection, and means controlled 15 by said apparatus for transmitting a timing signal at the beginning of each of such unit periods, said timing signal comprising said release signal followed by a canceling signal prior to release of the connection.

4. In a measured-service telephone system, subscribers' lines, individual message registers for said lines, a branch office, a main office, a conversational circuit unit in said main office for use in completing calls originating in said main office and for use in completing calls originating in said branch office, means for extending a connection from a calling line in said branch office to said unit, means for extending a connection from a calling line in said main office to said 20 unit, means in said unit for counting off unit periods of time during which a talking connection is maintained on calls originating in either of said offices, and means in said unit effective on a call originating in said main office to cause the 25 operation of the calling subscriber's message register upon establishment of a talking connection without repeating said charging operation thereafter during the continued maintenance of the connection.

5. In a measured-service telephone system, subscribers' lines, individual message registers for said lines, a branch office, a main office, a conversational circuit unit in said main office for use in completing calls originating in said main office 45 and for use in completing calls originating in said branch office, means for extending a connection from a calling line in said branch office to said unit, means for extending a connection from a calling line in said main office to said unit, means 50 in said unit for counting off unit periods of time during which a talking connection is maintained on calls originating in either of said offices, and means in said unit effective on a call originating in said main office to cause the operation of the 55 calling subscribers' message register upon establishment of a talking connection and for thereafter repeating said charging operation at the beginning of each succeeding period or part thereof.

6. In a measured-service telephone system, subscribers' lines, individual message registers for said lines, a branch office, a main office, a conversational circuit unit in said main office for use 65 in completing calls originating in said main office and for use in completing calls originating in said branch office, means for extending a connection from a calling line in said branch office to said unit, means for extending a connection from a calling line in said main office to said unit, means 70 in said unit for counting off unit periods of time during which a talking connection is maintained on calls originating in either of said offices, means in said unit for causing the operation of a calling 75

- subscriber's register upon establishment of a desired talking connection without repeating said charging operation during the continued maintenance of the connection, and means in said unit 5 for causing the operation of a calling subscriber's register upon establishment of a desired talking connection and for causing said charging operation to be repeated at the beginning of each succeeding unit period or part thereof.
- 10 7. In a measured-service telephone system, subscribers' lines, individual message registers for said lines, a branch office, a main office, a conversational circuit unit in said main office for use in completing calls originating in said main office and for use in completing calls originating in said branch office, means for extending a connection from a calling line in said branch office to said unit, means for extending a connection from a calling line in said main office to said unit, means in said unit for counting off unit periods of time during which a talking connection is maintained on calls originating in either of said offices, means in said unit for causing the operation of a calling subscriber's register upon establishment of a desired talking connection without repeating said charging operation during the continued maintenance of the connection, means in said unit for causing the operation of a calling subscriber's register upon establishment of a desired talking connection and for causing said charging operation to be repeated at the beginning of each succeeding unit period or part thereof, and means in said unit for terminating a talking connection at the end of a predetermined 35 number of said periods.
8. In a measured-service telephone system, subscribers' lines, individual message registers for said lines, a branch office, a main office, a conversational circuit unit in said main office for use in completing calls originating in said main office and for use in completing calls originating in said branch office, means for extending a connection from a calling line in said branch office to said unit, means for extending a connection from a calling line in said main office to said unit, means in said unit for counting off unit periods of time during which a talking connection is maintained on calls originating in either of said offices, means in said unit for causing the operation of a calling subscriber's register upon establishment of a desired talking connection without repeating said charging operation during the continued maintenance of the connection, means in said unit for causing the operation of a calling subscriber's register upon establishment of a desired talking connection and for causing said charging operation to be repeated at the beginning of each succeeding unit period or part thereof, means in said unit for terminating a talking connection at the end of a predetermined number of said periods, and means for transmitting a signal to a calling subscriber a short interval prior to the termination of said predetermined number of periods.
9. In a measured-service telephone system, a plurality of offices, subscribers' lines, service meters one for each of said lines, means in each of said offices for operating the service meter of a calling line, means in each of said offices for use in completing calls originating or terminating in the office in which said means is located, other means in one of said offices for use in completing calls originating in another office and terminating in another office, timing apparatus in said one of the offices for counting off predetermined 70 periods of time, and means responsive to the

answer of the called subscriber on any of said calls and controlled by said timing apparatus for causing the operation of the meter operating means in the office in which a call originates.

10. In a telephone system, a first office, a second office, a third office, subscribers' lines, service meters one for each of said lines, means including a trunk extending from said first office to said second office for use in completing calls originating in said first office and terminating in either of said other offices, means associated with said trunk in said first office for operating the service meter of a calling line, a link in said second office for use in completing calls incoming over said trunk and for use in completing calls originating in said second office, timing means in said second office for measuring off unit periods of time while a talking connection is maintained through said link, and means in said link for use in transmitting a timing signal over said trunk to said 15 second office, timing means in said second office for measuring off unit periods of time while a talking connection is maintained through said link, and means in said link for use in transmitting a timing signal over said trunk to said 20 second office, timing means in said second office for measuring off unit periods of time while a talking connection is maintained through said link, and means in said link for use in transmitting a timing signal over said trunk to said 25 second office, timing means in said second office for measuring off unit periods of time while a talking connection is maintained through said link, and means in said link for use in transmitting a timing signal over said trunk to said second office.

11. In a telephone system, a first office, a second office, a third office, subscribers' lines, service meters one for each of said lines, means including a trunk extending from said first office to said second office for use in completing calls originating in said first office and terminating in either of said other offices, means associated with said trunk in said first office for operating the service meter of a calling line, a link in said second office for use in completing calls incoming over said trunk and for use in completing calls originating in said second office, timing means in said second office for measuring off unit periods of time while a talking connection is maintained through said link, and means in said link for use in transmitting a timing signal over said trunk to said 30 second office, timing means in said second office for measuring off unit periods of time while a talking connection is maintained through said link, and means in said link for use in transmitting a timing signal over said trunk to said 35 second office, timing means in said second office for measuring off unit periods of time while a talking connection is maintained through said link, and means in said link for use in transmitting a timing signal over said trunk to said 40 second office, timing means in said second office for measuring off unit periods of time while a talking connection is maintained through said link, and means in said link for use in transmitting a timing signal over said trunk to said 45 second office, timing means in said second office for measuring off unit periods of time while a talking connection is maintained through said link, and means in said link for use in operating the service meter of a calling line on calls originating in said second office.

12. In a multi-office telephone system, subscribers' lines, service meters one for each of said lines, an impulse dial at each subscriber's station for use in establishing a desired connection, means including a trunk extending from a first office to a second office for use in completing calls originating in said first office and terminating in another office, means in said first office and associated with said trunk for registering in response to digits dialed by a calling subscriber the zone destination of the call, timing means in said second office for counting off unit periods of time while a talking connection is maintained over said trunk and for transmitting a signal at the beginning of each of said periods over said trunk, and charging means in said first office set in operation upon receipt of each of said timing signals for operating the calling subscriber's meter one or more times, the number of meter operations being controlled by said zone registering means.

13. In a telephone system, a branch office, a main office, measured-service subscribers' lines in each of said offices, individual meters for said lines, other subscribers' lines, a trunk for use in extending a call from a calling line in said branch office to said main office, means in said branch 75

- office associated with said trunk for use in operating the meter of a calling line in the branch office, a link in said main office for use in completing calls originating in said main office and for use 5 in completing calls incoming to said main office over said trunk, means associated with said link for counting off unit periods of time during which a talking connection is maintained on calls originating in either of said offices, and means in said 10 link effective on a call originating in said branch office for transmitting at the beginning of each of said unit periods of time a signal to cause the operation of said meter operating means in the branch office.
- 15 14. In a telephone system, a branch office, a main office, measured-service subscribers' lines in each of said offices, individual meters for said lines, other subscribers' lines, a trunk for use in extending a call from a calling line in said branch office to said main office, means in said branch office associated with said trunk for use in operating the meter of a calling line in the branch office, a link in said main office for use in completing calls originating in said main office and calls in 20 25 coming to said main office over said trunk, means associated with said link for use in operating the meter of a calling subscriber in said main office, timing mechanism associated with said link for measuring off unit periods of time while a talking connection is established through said link, and means effective on a call originating in said branch office and comprising the meter operating means associated with said link and said timing mechanism for transmitting to said branch office 30 35 a signal over said trunk to render effective said meter operating means in said branch office.
15. In a measured-service telephone system, subscribers' lines, individual message registers for said lines, a branch office, a main office, a conversational circuit unit in said main office for use 40 45 in completing calls originating in said main office and for use in completing calls originating in said branch office means for extending a connection from a calling line in said branch office to said unit, means for extending a connection from a calling line in said main office to said unit, means in said unit for counting off unit periods of time during which a talking connection is maintained on calls originating in either of said offices, means 50 in said unit operatively responsive to the answer
- of the called subscriber for causing the operation of the calling subscriber's register, and means effective during the continuance of the talking connection on calls other than calls local to said main office for causing said operation of the calling subscriber's register to be repeated at the beginning of each succeeding measured period of time. 5
16. In a measured-service telephone system, subscribers' lines, individual message registers for said lines, a branch office, a main office, a conversational circuit unit in said main office for use in completing calls originating in said main office and for use in completing calls originating in said branch office, means for extending a connection from a calling line in said branch office to said unit, means for extending a connection from a calling line in said main office to said unit, means in said unit for counting off unit periods of time during which a talking connection is maintained on calls originating in either of said offices, means in said unit and operatively effective on calls local to said main office for causing the operation of the calling subscriber's register upon establishment of a desired talking connection without repeating said charging operation during the continued maintenance of the connection, and means in said unit and operatively effective on all calls except calls local to said main office for causing the operation of the calling subscriber's register upon establishment of a desired talking connection and for causing said charging operation to be repeated at the beginning of each succeeding unit period or part thereof. 15 20 25 30 35
17. In a measured-service telephone system according to claim 16, means in said conversational circuit unit for terminating a talking connection at the end of a predetermined number of said measured unit periods of time. 35
18. In a measured-service telephone system according to claim 16, means in said conversational circuit unit for terminating a talking connection at the end of a predetermined number of said measured unit periods of time, and means for transmitting a signal to a calling subscriber a short interval prior to the termination of said predetermined number of measured-periods of time. 40 45 50
